US00D756952S

(12) **United States Design Patent**
Simonian et al.

(10) **Patent No.:** **US D756,952 S**
(45) **Date of Patent:** **** May 24, 2016**

(54) **PORTABLE ELECTRONIC DEVICE**

(71) Applicant: **HTC Corporation**, Taoyuan, Taoyuan County (TW)

(72) Inventors: **Michael Arthur Simonian**, San Francisco, CA (US); **Daniel Hundt**, San Francisco, CA (US); **Hannes Jens Dieter Harms**, San Francisco, CA (US); **Jenny Y. Lee**, San Francisco, CA (US); **Geoffrey Michael Hill**, San Francisco, CA (US)

(73) Assignees: **HTC CORPORATION**, Taoyuan (TW); **GOOGLE INC.**, Mountain View, CA (US)

(**) Term: **14 Years**

(21) Appl. No.: **29/496,666**

(22) Filed: **Jul. 16, 2014**

(51) LOC (10) Cl. **14-03**

(52) U.S. Cl.

(57) **CLAIM**

The ornamental design for portable electronic device, as shown and described.

DESCRIPTION

FIG. 1 is a front perspective view of a first embodiment of a portable electronic device in accordance with our new design;

FIG. 2 is a front view thereof;

FIG. 3 is a rear view thereof;

FIG. 4 is a left side view thereof;

FIG. 5 is a right side view thereof;

FIG. 6 is a top plan view thereof;

FIG. 7 is a bottom plan view thereof;

FIG. 8 is a rear perspective view thereof;

FIG. 9 is a front perspective view of a second embodiment of a portable electronic device in accordance with our new design;

FIG. 10 is a front view thereof;

FIG. 11 is a rear view thereof;

FIG. 12 is a left side view thereof;

FIG. 13 is a right side view thereof;

FIG. 14 is a top plan view thereof;

FIG. 15 is a bottom plan view thereof; and,

FIG. 16 is a rear perspective view thereof.

The broken lines shown in the figures that are immediately adjacent to the claim, and define unshaded regions, represent the bounds of the claim, while all other broken lines are directed to environment; the broken lines form no part of the claimed design.

1 Claim, 14 Drawing Sheets
